PEN FOR RULING MACHINES

Filed Nov. 7, 1929

Inventor,

Albert Broadmeyer

By

R. J. Foster

Attorney

UNITED STATES PATENT OFFICE

ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA

PEN FOR RULING MACHINES

Application filed November 7, 1929. Serial No. 405,504.

In certain modern ruling machines which are operable at high speed, difficulty has been experienced in "striking" due to the spattering of the ink from the pens. This to some extent is due to the vibration or shivering of the pen because of its quick lifting and dropping movements.

One of the objects of the present invention is to provide a pen structure that is stiffer at the place where the pen is bent between the shank or back and the point, which place is the weakest, the stiffening means thereby preventing the shivering or vibration of the point during the vertical swinging movements thereof and also incidentally acting as an additional anchoring means that prevents lateral displacement of the pen in the pen holder or carrier.

In the embodiment disclosed:

20 Figure 1 is a cross sectional view through a modern form of pen beam showing a pen therein, the pen being illustrated in longitudinal section.

25 Figure 2 is a front elevation of the structure illustrated in Figure 1.

Figure 3 is a sectional view on the line 3—3 of Figure 1.

Figure 4 is a plan view of the pen.

Figure 5 is a perspective view of the same.

30 Figure 6 is a side elevation of said pen.

Figure 7 is a top plan view of a modified form of construction.

Figure 8 is a perspective view of the pen shown in Figure 7.

35 Considering the embodiment disclosed in Figures 1—6 inclusive, the pen is formed of a strip of sheet metal and comprises a flat relatively wide shank 9 with the usual narrower point portion or bowl 10. This shank portion is provided with a bend 11 so that the bow or point portion 10 is disposed at an angle to the shank portion 9. The point portion has its side walls bent upwardly to form a channel 12 and in the present embodiment this channel is extended through the offset part 13 of the shank 9 and longitudinally into said shank, so that an extension 14 of the channel bridges the bend 11 of the shank. As a consequence the bend or angle is materially stiffened so that when the pen is mount-

ed in a beam or other carrier, it will not vibrate. Incidentally in the formation of the channel there is produced on the underside of the shank a longitudinally disposed rib 16.

The pen is mounted in the usual manner. 55 That is to say, as shown in Figures 1, 2 and 3, the pen beam or carrier comprises a supporting bar 17 with an overlying clamping bar 18, and the shank 9 of the pen is clamped between the two. Preferably the supporting bar 17 has a bed 19 of rubber or other yielding material. Therefore when the shank is clamped, as clearly shown in Figures 1 and 3, the rib 16 will be bedded in the cushions 19 and consequently the pen will be held 60 65 against lateral displacement.

In Figures 7 and 8 the structure is substantially the same as that above described except that the channel is extended substantially the full length of the shank. Thus 70 the shank in these figures is designated 9a and the point or bowl member 10a. The channel is illustrated at 14a and as shown bridges the bend 11a. The advantages are 75 the same in this form of structure as in that first described.

It will be evident that this device, while simple in construction, has decided advantages over that usually employed in which the shank at the bend is flat so that it constitutes 80 a relatively weak line on which the pen point vibrates vertically. Preferably in the formation of the structure the groove or channel 14—14a is formed after the bend 11—11a has been made, it being found that this produces a stronger structure. 85

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention. 90 95

What I claim, is:

A pen for ruling machines, comprising a sheet metal strip having a broad substantially flat shank portion and a narrower bowl or 100

point portion disposed at an obtuse angle to the shank portion and having its upper side longitudinally channeled, the channel of the bowl or point portion extending into the upper side of the shank portion and forming a rib on the underside of said shank portion for interlocking with the material of the pen beam.

In testimony whereof, I affix my signature.

ALBERT BROADMEYER.
